[57] CLAIM

The ornamental design for a dual headed flashlight, as shown and described.

DESCRIPTION

FIG. 1 is a side view of the dual headed flashlight;

FIG. 2 is a bottom view;

FIG. 3 is a top view;

FIG. 4 is a front, elevational view;

FIG. 5 is a rear view;

FIG. 6 is a bottom view when the lower lens unit of the dual headed flashlight is rotated away from the upper lens unit;

FIG. 7 is a side view of the flashlight with the lower lens rotated away from the upper lens;

FIG. 8 is a rear view of the flashlight with the lower lens rotated away from the upper lens; and,

FIG. 9 is a front, elevational view of the flashlight with the lower lens rotated away from the upper lens.

The phantom lines do not form part of the claimed design.
